UNITED STATES PATENT OFFICE

OSCAR M. ANDERSON AND FRED W. JUENGST, OF NEW BRITAIN, CONNECTICUT, ASSIGNORS TO LANDERS, FRARY & CLARK, OF NEW BRITAIN, CONNECTICUT, A CORPORATION OF CONNECTICUT

DESIGN FOR A COFFEE MAKER

Application filed April 30, 1932. Serial No. 43,682. Term of patent 14 years.

To all whom it may concern:

Be it known that we, OSCAR M. ANDERSON, a subject of the King of Sweden, and FRED W. JUENGST, a citizen of the United States, both residing at New Britain, in the county of Hartford, State of Connecticut, have invented a new, original, and ornamental Design for a Coffee Maker, of which the following is a specification, reference being had to the accompanying drawing, forming part hereof.

In said drawing:

Fig. 2 is an end elevation thereof; and

Fig. 3 is a top plan view.

We claim:

The ornamental design for a coffee maker as shown.

OSCAR M. ANDERSON.
FRED W. JUENGST.
